UNITED STATES PATENT OFFICE.

THEODORE P. BROWN, OF WORCESTER, MASSACHUSETTS.

TRACKER-BOARD FOR AUTOMATIC MUSICAL INSTRUMENTS.

SPECIFICATION forming part of Letters Patent No. 735,062, dated August 4, 1903.

Application filed January 2, 1903. Serial No. 137,461. (No model.)

To all whom it may concern:

Be it known that I, THEODORE P. BROWN, a citizen of the United States, residing at Worcester, in the county of Worcester and State of Massachusetts, have invented a new and useful Tracker-Board for Automatic Musical Instruments, of which the following is a specification.

This invention relates to the "tracker-boards," so termed, which are employed in automatic musical instruments—that is, this invention relates to those boards or pieces having channels coöperating with the sheets of perforated paper.

The especial object of this invention is to provide a tracker-board construction of the same general color or finish as the casings employed in musical instruments of this class and which at the same time will be provided with a light-colored central guiding-face surrounding the perforations, which light-colored face will show the registration of the perforations in the paper with the holes of the tracker-board.

To these ends this invention consists of the tracker-board as an article of manufacture, as hereinafter described, and more particularly pointed out in the claims at the end of this specification.

The accompanying drawing shows a perspective view of a tracker-board constructed according to this invention.

In the use of that class of automatic musical instruments which are controlled by perforated sheets of paper the best results can only be obtained when perfect registration is maintained between the perforations of the music-sheet and the holes in the tracker-board. In order that the registration of the music-perforations with the holes of the tracker-board may be readily observed, it is essential that the tracker-board should be of a light color, and it is on this account that in substantially all the automatic musical instruments which are now manufactured the tracker-boards are made of light-colored woods. It results from this that when the casing of an automatic musical instrument is opened the light coloring of the tracker-board will necessarily present an unfinished and for many purposes unattractive appearance. On this account a demand has arisen that the

tracker-boards should have substantially the same finish or coloring as the casing of the instrument itself; but it has been found impossible in practice to employ dark-colored tracker-boards to produce the best results, as when the music-sheet is drawn over the face of the dark-colored tracker-board it is substantially impossible to distinguish whether the perforations of the music-sheet are registering accurately with the tracker-board holes. To overcome this objection, I have found in practice that it is not essential that the entire face of the tracker-board should be light-colored in order to permit an accurate observation of the music-sheet, but that a comparatively narrow light-colored strip on the face of the tracker-board will be sufficient for showing whether the music-sheet is properly positioned or not. By taking advantage of this fact I have been enabled to provide a tracker-board the body portion or greater part of which may be of the same coloring as the casing of the instrument, while the face of the tracker-board may be provided with a comparatively narrow light-colored strip surrounding the perforations, so as to provide means for registering the music with the tracker-board holes.

Referring to the accompanying drawing for a detailed description of a tracker-board constructed according to my invention, the tracker-board A is provided with the usual holes. Surrounding the tracker-board holes H is a light-colored registering face or strip S, while the body portion of the tracker-board is of a dark or deep colored finish, which may correspond with the casing of the instrument in which the tracker-board is to be used. The contrasted effect of the registration-strip S and the body portion of the tracker-board may be secured by painting, staining, or in some cases veneering the surface of the tracker-board, leaving the registration-strip S exposed in the natural color of the wood from which the tracker-board is made, or in some cases this result can be obtained by inlaying a registration-strip S into the face of the tracker-board.

I am aware that changes may be made in the construction of my tracker-board without departing from the scope of my invention as expressed in the claims. I do not wish,

therefore, to be limited to the special tracker-board I have herein shown and described; but

What I do claim, and desire to secure by Letters Patent of the United States, is—

- 5 1. As an article of manufacture, a tracker-board for use in automatic musical instruments having a dark-colored body portion which may correspond with the finish of the casing of the instrument in which the tracker-board is to be used and having a light-colored registration-surface surrounding the tracker-board holes.
- 10 2. As an article of manufacture, the tracker-board A for automatic musical instruments, having a dark-colored body portion which
- 15

may correspond with the coloring of the casing of the instrument in which the tracker-board is to be used and having a light-colored registration-strip S surrounding the tracker-board holes H and narrower than the surface 20 of the upper face of the tracker-board, substantially as described.

In testimony whereof I have hereunto set my hand in the presence of two subscribing witnesses.

THEODORE P. BROWN.
